(57) **CLAIM**

The ornamental design for a shawl, as shown and described.

DESCRIPTION

FIG. 1 is a perspective view of a shawl showing my new design;

FIG. 2 is a front elevational view thereof;

FIG. 3 is a rear elevational view thereof;

FIG. 4 is an enlarged view of portion 4 shown in FIG. 1; and, FIG. 5 is a front elevational view of a shawl, showing how the shawl would appear when being worn.

The broken lines in FIG. 4 depict the boundaries of the enlargements that form no part of the claimed design. The broken line outline of the partial human mannequin figure in FIGS. 5 assists in illustrating the shawl in a position of use, but forms no part of the claimed design.
